His Attorney.

UNITED STATES PATENT OFFICE.

THEODORE A. LANSCHA, OF FLANAGAN, ILLINOIS, ASSIGNOR OF ONE-HALF
TO HARMON LOCKER, OF SAME PLACE.

PLOW.

SPECIFICATION forming part of Letters Patent No. 291,524, dated January 8, 1884.

Application filed August 2, 1883. (No model.)

To all whom it may concern:

Be it known that I, THEODORE A. LANSCHA, of Flanagan, in the county of Livingston, in the State of Illinois, have invented an Im-
5 proved Plow; and I do hereby declare that the following is a full, clear, and exact descrip-
tion thereof, reference being had to the an-
nexed drawings, making a part of this speci-
fication, in which like letters of reference re-
fer to like parts, and in which—

Figure 1 represents a side elevation of my in-
vention; Fig. 2, a side elevation of a modifica-
tion.

The object of this invention is the construc-
15 tion of a plow that shall be of as light draft as
possible, and also be so evenly balanced as to
run perfectly level in the ground, neither with
its nose tending to come up to the surface or
rooting down too deep in the ground. To
20 achieve these results, I make, in the first place,
my beam six inches shorter than is customary,
and then set it back upon the landside several
inches farther still.

In the drawings, B represents the beam of
25 the plow; A, the clevis; C, the standard; G,
the landside; F, the mold-board; E, the nose
or point of the plowshare, and H H' the stilts
or handles.

In Fig. 1, the beam B and standard C are
30 shown formed in one piece of cast-iron, while
Fig. 2 shows the beam B' and standard C as
separate, the former of wood and the latter of
iron. From the standard C extends forward
35 and downward a brace, D, cast as an integral
part of said standard C. The lower end of
this brace is fastened to the landside G about
five inches behind the share E. To the stand-
ard C is secured the left handle, H, the upper
40 portion of which is strengthened vertically by
the brace-rod M. The right handle, H', is

rigidly attached to the mold-board F by means
of the projecting lugs H² and the brace-rod J,
having a right-hand thread on one end and a
left-hand thread on its other, whereby it can
be screwed at one end into the standard C and
45 at its other extremity into both the handle H'
and the mold-board F. This brace-rod J sup-
ports the said mold-board against the pressure
of the furrow-slice. The said lugs H² are made
farther apart than the width of the handle H,
50 and also approach each other outwardly. A
small wedge being driven in between one of
the lugs and the side of the handle H', the lat-
ter is firmly held in place. In the case of
a wooden beam B, the standard C and its brace
55 D are still cast, as before, in one piece, and
also another brace or arm, D', projecting up-
ward and backward to the extreme rear end
of the beam B. Both the upper ends of the
standard and brace D' are bolted to the beam
60 B. The handles are secured to the mold-board
and the standard, as before described.

What I claim as my invention, and for which
I desire Letters Patent, is as follows, to wit:

In plows of that kind in which a shortened
beam, B, has its standard C fastened to the
65 rear extremity of the landside G and is stiff-
ened by the forwardly-projecting brace D, the
handles H H' and brace-rod M, in combina-
tion with the mold-board F, having dovetail
70 lugs H², and a wedge, by means of which one
of said arms, H', is rigidly secured to said
mold-board, as set forth.

In testimony that I claim the foregoing in-
vention I have hereunto set my hand this 28th
75 day of June, 1883.

THEODORE A. LANSCHA.

Witnesses:

GEOORG HOVILL,
HENRY LINNEMAN.
